James H. Poome

UNITED STATES PATENT OFFICE.

JAMES H. ROOME, OF NEW YORK, N. Y.

SHEARS.

Specification of Letters Patent No. 25,140, dated August 16, 1859.

To all whom it may concern:

Be it known that I, JAMES H. ROOME, of the city, county, and State of New York, have invented a new and useful Improvement 5 in Tailors' and other Shears, which may also be applied to other cutting instruments; and I do hereby declare that the following is a full, clear, and exact description of the same, reference being had to the accompanying drawings, forming part of 10 this specification, in which—

Figures 1 and 2 are opposite side views of a pair of shears constructed according to my invention. Fig. 3 is a top view of the 15 same. Fig. 4 is a transverse section of the same in the same line α , α , of Fig. 1.

Similar letters of reference indicate corresponding parts in the several figures.

My invention consists in a certain mode 20 of combining one limb of a pair of shears or other hand cutting instrument with a handle forming part of a separate lever and combining the said limb and handle with the other limb of the shears whereby the 25 leverage exerted by the thumb or hand in cutting is gradually increased as the shears close and a drawing cut is produced.

To enable others skilled in the art to make and use my invention I will proceed to 30 describe its construction and operation.

A is the blade, and B, the handle, which combine to form the lower limb of the shears, made in one piece and of such form 35 that the handle as well as the blade may rest upon the cutting board or table during the cutting operation. At the junction of the blade and handle this limb is made much deeper than is common in other shears, in order that the pin a , on which the upper 40 blade works may be arranged some distance above the edge of the lower blade.

C, D, is the upper limb made in the form 45 of a lever of which the upper blade C, constitutes one arm, and the other arm D, is extended rearward from the said blade and from the point where this limb is attached to the lower limb by the pin a . This upper limb is made deep enough below the point where it receives the pin a , to reach nearly 50 to the bottom of the limb A B, as shown in Fig. 1, and below the pin a , it contains a slot b , having the form of an arc described from the pin a , said slot receiving a broad headed screw c , which screws into the lower limb, and the part of the upper limb surrounding the said slot being rather thicker

at that end of the said slot nearest the blade than at the other end thereof, so that in the closing of the shears the faces of the blades will be drawn toward each other or gradually pressed tighter against each other. The arm D, contains a slot d , to receive a pin e , which is carried by an arm f , which is attached to the lever of which the upper handle of the shears forms a part, and whose 60 duty will be hereinafter explained.

E, is the upper handle constituting a portion of a lever E G, and attached to the lower limb of the shears by a fulcrum pin g , which is situated much nearer to the front 70 end than to the rear end which terminates in the thumb bow. A slot h , is provided in the said lever E G, for the fulcrum pin g , to pass through to permit the said handle a longitudinal, as well as a lever-like movement, and the said pin g , is fitted with an antifriction roller within the said slot. The front end of the said lever is connected with the upper limb C D, by a link F, and two joint pins i , j , the pin j , which attaches the 75 said link to the said limb being arranged a little in rear of and some distance below the pin a , and the pin i , which attaches the said link to the lever E G, being so arranged that when the shears are closed the said link 80 will be parallel or nearly so with the edges of the blades. The arm f , which has been before mentioned, is attached to the front extremity of the lever E G, and stands up nearly at a right angle to the portion of the 85 said handle that is in front of the fulcrum pin g , and the said arm is made of forked form, as shown in Fig. 4, to receive the arm D, of the upper limb. The fork of the said arm f , also contains a roller k , which turns 90 on a pin l , inserted through the said arm; and above the said roller is the before mentioned pin e , working in the slot in the arm D, of the upper limb. The roller k , works against the bottom of the arm D, of the 95 upper limb, for the purpose of forcing up the said arm D, and bringing down the blade C to effect the cutting operation by the depression of the handle E; and the pin e , is for the purpose of drawing down the arm D, to open the shears as the handle E, is raised. To provide for the grinding away of the blades by repeated sharpenings of the shears and insure the proper closing of the shears and their cutting to the points when ground away, the arm f , is made detached from the lever E G, and is secured

thereto by a screw *m*, passing through a slot *n*, in the said arm and screwing into the said lever *E*. The slot *n*, permits the adjustment of the said arm *f*, higher or lower and to keep the said arm steady and prevent its being forced out of place by the force applied to it in cutting, there is a steady pin *p* projecting from the lever *E G*, into the said slot *n*, and there are a series of teeth and notches *q q*, provided in the said arm, as shown in Figs. 1 and 4, and in the face of the lever to which it is attached.

H, is a spring secured to the lower limb *A B*, of the shears, and pressing against an anti-friction roller *r*, attached to the lever *E G*, for the purpose of raising and throwing forward the rear or lower end of the said lever and so opening or assisting in opening the shears when the said lever is relieved from the pressure of the thumb or hand.

In operating with these shears the lower limb is allowed to rest on the cutting board or table; and the cut is produced by depressing the upper handle, and, at the same time, pulling or pressing it in a backward direction from the position shown in Fig. 2, and in black outline in Fig. 1. This movement of the handle causes the front end of the lever *E G*, which is connected with the upper limb to rise, and the arm *f*, to move backward, and so cause the roller *k*, to pass along the lower edge of the arm *D*, of the upper limb, and so depress the upper blade *C*; but, at the same time, the end of the link *F*, which is attached to the rising front end of the lever *E G*, is raised by the said lever and the said link is forced bodily backward by the movement of the limb *C D*, and so caused to force back the said lever bodily on its fulcrum *g*, thus gradually increasing the length of the said lever behind the said pin and diminishing its length in front thereof,

and so increasing its power as the blade *C*, descends and while this increase of power of the said lever is taking place, the roller *k*, in gradually receding from the pin *a*, or fulcrum of the upper limb *C D*, is also causing the power applied by the said lever to act with increased effect on the blade, and thus the power exerted by the hand is increased as the cutting takes place farther from the pin or fulcrum *a*, and diminishes a greater resistance to the closing of the blades. This operation is illustrated in Fig. 1, by the representation of the shears in a closed condition, in red outline. The operation of the shears is also greatly assisted by the drawing cut that is caused by the elevated position of the pin *a*.

The same construction may be adapted, with some advantage, to hand punches, the punch being attached to the lever *C D*.

What I claim as my invention, and desire to secure by Letters Patent, is:—

Combining one limb *C D*, of a pair of shears, or other similarly operating hand cutting instrument, with its handle *E*, forming part of a separate lever *E G*, and combining the said limb and handle with the other limb of the shears, by means of an arm *f*, attached to the said lever *E G*, and operating on the rear portion *D*, of the first mentioned limb, a link *F*, connecting the said limb with the said lever, and a movable fulcrum connection *g*, *h*, between the said lever and the other limb; the whole operating substantially as described to cause the power of the said lever to increase as the shears close.

JAMES H. ROOME.
